(74) Attorney, Agent, or Firm—Pearne & Gordon LLP

(57) **CLAIM**

The ornamental design for table storage system, as shown and described.

DESCRIPTION

FIG. 1 is a bottom, front, and right side perspective view of a table storage system showing my new design;

FIG. 2 is a front elevational view thereof;

FIG. 3 is a left side elevational view thereof;

FIG. 4 is a bottom plan view thereof; and,

FIG. 5 is a bottom and side perspective view thereof.

The broken-line disclosure in the views forms no part of the claimed design.
